UNITED STATES PATENT OFFICE.

IRVING STANLEY, OF NEW YORK, N. Y.

MUFFLER CUT-OUT.

1,227,212.

Specification of Letters Patent. Patented May 22, 1917.

Application filed July 19, 1916. Serial No. 110,173.

To all whom it may concern:

Be it known that I, IRVING STANLEY, a citizen of the United States, residing at New York, in the county of New York and State 5 of New York, have invented certain new and useful Improvements in Muffler Cut-Outs, of which the following is a specification.

This invention relates to muffler cutouts 10 for gas engines, such as those commonly used with automobiles, although it is well adapted for all classes of gas engines where a muffler cutout is desirable, the object of the invention being to provide a simple, 15 comparatively inexpensive, durable and reliable as well as effective muffler cutout which can be readily and quickly applied to the exhaust pipe of the gas engine thereby to interrupt the passage of the exhaust gases 20 from the engine through the muffler and permit the same to pass into the atmosphere without passing through the muffler or to permit the same to pass into the muffler without the choking thereof.

25 In the drawings accompanying and forming part of this specification, Figure 1 is a top view of the present improvement; Fig. 2 is a longitudinal sectional view taken in line 2—2, Fig. 3; Fig. 3 is a cross-sectional view taken in line 3—3, Fig. 2, the dotted lines illustrating the open position of the cutout; Fig. 4 is a detail sectional view taken in line 4—4, Fig. 3, looking in the direction of the arrow; and Figs. 5 and 6 are side and 30 end views of another form of this improved muffler cutout in which a plurality of enlarged chambers are shown.

Similar characters of reference indicate 40 corresponding parts in the different figures of the drawings.

In the preferred form thereof herein shown and described, the exhaust pipe leading from the engine to the muffler is shown in the present instance as made of two parts, 45 the part 2 leading from the engine and the part 3 leading to the muffler, and in practice when this exhaust pipe is made as one continuous member a piece is cut therefrom to form two spaced ends 4 upon which this 50 improved muffler cutout is located. The muffler cutout comprises a two-part casting 5 forming an enlarged chamber 6 shown materially larger in diameter than the diameter of the exhaust pipe, and one part or member of this chamber, as 7, is rigidly clamped by means of a sleeve 8 and clamping bolt 9

upon one of the ends of the pipe, it being shown in the present instance as being clamped to that section of the pipe, as 3, leading to the muffler, whereby this part of 60 the muffler cutout is rigid with the pipe. The other member 7' of the muffler cutout is mounted for rotary movement relatively to the member 7, and for this purpose the sleeved end 10 thereof is supported by a 65 bushing or sleeve 11 likewise bolted by a bolt 12 to that section of the pipe, as 2, leading from the engine, the member 7' being rotatable upon this sleeve, and for which purpose the sleeve is recessed at 13 to 70 have a part thereof, as 14, fit the sleeved end 10 of the cutout part 7'. The fixed muffler member 7 and the sleeve 11 are each provided with a flange or collar 15 against which the ends of the pipe sections 2 and 3 75 fit, these flanges or collars 15 forming an opening or passage of substantially the same diameter as the pipe sections 2 and 3, whereby tight engagements of the pipes with the muffler cutout part 7 and sleeve 11 are obtained and a similar tight engagement between the sleeved end 10 of the muffler part 7' and the sleeve 11 is also obtained by reason of the annular recess 13 hereinbefore referred to. Each of the muffler members or 80 parts 7 and 7' is provided with a depending wall 16 and 16', through which extends a slotted bolt or pin 17 threaded into the depending wall 16', which pin or bolt is in axial alignment with the rotary axis of the 85 muffler part 7' upon the sleeve of that part of the pipe leading from the engine. These depending walls 16 and 16' form a baffle plate and compel the exhaust gases to pass 90 from the pipe 2 to the pipe 3 when the cutout is closed substantially as shown in Fig. 2, and when the cutout is open this baffle plate deflects the gases so that they will 95 more effectively pass into the open air and thus prevent any appreciable part thereof 100 from passing to the muffler.

Any suitable means may be used for swinging the muffler cutout part 7'. In the present instance a rod or wire 18 is shown connected with a lug 19 secured to 105 the muffler cutout part 7' which may lead to any suitable operating device, as a pedal or otherwise, whereby the muffler part 7' may be rotated upon its axis relatively to the fixed part 7 thereby to interrupt the 110 communicating passage to the muffler and permit the exhaust gases to pass into the

atmosphere without passing through the muffler. For returning the shiftable part 7' to its closed position a suitable spring may be used, and in the present instance 5 a coiled spring 20 has one end secured in a slot 21 of the bolt or pin 17 hereinbefore referred to while the other end is secured to a bolt 22 threaded into the depending wall 16 of the fixed part of the muffler cut- 10 out, so that when the rotary part of the muffler cutout is swung open it will rotate upon the sleeve secured to that section of the pipe leading from the engine and tighten the spring so that when the cutout 15 is released the spring will return to its normal position.

Any suitable means may be used for maintaining the meeting edges of the parts 7 and 7' of the muffler cutout in gas-tight 20 engagement, such as by forming one of those edges inclined relatively to the other. In the present instance the fixed part 7 is provided with a depending L-shaped portion 23 having bolted thereto an upwardly 25 extending member 24 forming a recess 25 for a depending lip 26 of the shiftable member 7', and this lip is provided with an inclined or curved surface 27 forming a cam surface adapted to coöperate with 30 the straight surface 28 of the member 24, whereby when the spring returns the movable member to its closed position the co-acting cam surfaces will wedge the two members in relatively tight engagement.

35 For properly maintaining the two parts in juxtaposition the fixed part 7 and the sleeve 11 are provided with a pair of laterally extending ears 29 for the reception of a pair of bolts 30 and suitable castellated nuts 31, and on each of these bolts and between its nut and one of the ears is located a spring 32 whereby the two parts of the cutout will be sufficiently tightly held together while permitting rotary movement 40 of one of the parts thereof. By means of this arrangement different tensions may be obtained upon the two cutout parts, and when the desired tension is obtained by the adjustment of the castellated nuts to press 45 or release the spring as the case may be then suitable pins or cotter pins 33 may be inserted to maintain this tension, and which pins will of course prevent the nuts from working loose. By forming the two parts 50 7 and 7' in the manner shown in Fig. 2, with the diameter thereof materially enlarged, it will be observed that the exhaust gases have an opportunity to expand within the chamber 6 of the cutout before passing 55 to the muffler, so that any choking action of the gases is avoided while at the same time when the rotary part 7' is swung into the dotted line position shown in Fig. 3 this enlarged chamber of the cutout pro- 60 vides a relatively large opening for the 65

quick and immediate passage of the exhaust gases from the engine.

In the form of the invention shown in Figs. 5 and 6 the cutout, constructed in substantially the same manner hereinbefore described, is provided with a pair of enlarged portions or chambers 6' and 6'' 70 instead of one chamber 6 as shown in Fig. 3. In other words, instead of the single depending enlarged chamber shown in Fig. 3 75 the cutout is provided with a similar large portion diametrically opposite to that shown in Fig. 3, the construction and mode of operation being otherwise the same if desired. Figs. 5 and 6 are therefore merely 80 illustrative of the fact that a plurality of enlarged portions may be provided if desired. In practice a suitable stop 35 is provided carried by the fixed part 7 and against which the swinging part of the cutout 85 engages to limit the closing movement of the latter.

From the foregoing it will be observed that I have provided an improved cutout 90 having one or more enlarged chambers as compared with the diameter of the exhaust pipe, and which chamber or chambers are formed by a casting consisting of a fixed member and a rotary member rotatable on the pipe relatively to the fixed member 95 either to cutout the muffler or open communication from the engine therewith, together with suitable means for maintaining the two parts in proper tensioned relation with each other and for returning the 100 swinging part to its closed position, and for wedging such parts in such closed position. It will be understood that the various details may be more or less changed without departing from the spirit and scope 105 of the present improvement.

I claim as my invention:

1. The combination with an exhaust pipe having a pair of spaced ends, of a muffler cutout comprising a two-part casing having one part fixed relatively to one of said ends and the other part rotatable relatively to the other end and to said fixed part thereby to open or close communication between said ends. 110

2. The combination with an exhaust pipe having a pair of spaced ends, of a muffler cutout comprising a two-part casing having one part fixed relatively to one of said ends and the other part rotatable relatively to the other end and to said fixed part thereby to open or close communication between said ends, means for rotating said rotatable part, and means for returning it to its normal position. 120

3. The combination with an exhaust pipe having a pair of spaced ends, of a muffler cutout comprising a two-part casing having one part fixed relatively to one of said ends and the other part rotatable relatively to 125 130

the other end and to said fixed part thereby to open or close communication between said ends, means for rotating said rotatable part, and means for returning it to its normal position, said last means comprising a spring.

4. The combination with an exhaust pipe having a pair of spaced ends, of a muffler cutout comprising a two-part casing having

10 one part fixed relatively to one of said ends and the other part rotatable relatively to the other end and to said fixed part thereby to open or close communication between said ends, means for rotating said rotatable part, and means for returning it to its normal position, said last means comprising a spring connected with said casing parts.

5. The combination with an exhaust pipe having a pair of spaced ends, of a muffler 20 cutout comprising a two-part casing having one part fixed relatively to one of said ends and the other part rotatable relatively to the other end and to said fixed part thereby to open or close communication between 25 said ends, means for rotating one of said parts relatively to the other, means for returning said rotatable part to its normal position, and means for wedging the said parts in closed position relatively to each 30 other.

6. The combination with an exhaust pipe having a pair of spaced ends, of a muffler cutout comprising a two-part casing having one part fixed relatively to one of said ends 35 and the other part rotatable relatively to the other end and to said fixed part thereby to open or close communication between said ends, means for rotating one of said parts relatively to the other, means for returning said rotatable part to its normal 40 position, and means for wedging the said parts in closed position relatively to each other and comprising cam surfaces carried by said casing parts.

45 7. The combination with an exhaust pipe having a pair of spaced ends, of a muffler cutout comprising a two-part casing having one part fixed relatively to one of said ends and the other part rotatable relatively to the 50 other end and to said fixed part thereby to open or close communication between said ends, and means for maintaining said casing parts in tensioned relation relatively to each other.

55 8. The combination with an exhaust pipe having a pair of spaced ends, of a muffler cutout comprising a two-part casing having one part fixed relatively to one of said ends and the other part rotatable relatively to the 60 other end and to said fixed part thereby to open or close communication between said ends, and means comprising a spring for returning the rotatable part to its closed position.

65 9. The combination with an exhaust pipe

having a pair of spaced ends, of a muffler cutout comprising a two-part casing having one part fixed relatively to one of said ends and the other part rotatable relatively to the other end and to said fixed part thereby to open or close communication between said ends, and means for wedging said casing parts when in their normal closed position.

10. The combination with an exhaust pipe 75 having a pair of spaced ends, of a muffler cutout comprising a two-part casing having one part fixed relatively to one of said ends and the other part rotatable relatively to the other end and to said fixed part thereby to open or close communication between 80 said ends, means for maintaining said casing parts in tensioned relation relatively to each other, means for returning the rotary part to its normal closed position, and means for 85 wedging said parts in such closed position.

11. The combination with an exhaust pipe having a pair of spaced ends, of a muffler cutout comprising a two-part casing having one part fixed relatively to one of said ends 90 and the other part rotatable relatively to the other end and to said fixed part thereby to open or close communication between said ends, said casing having one or more enlarged chambers.

12. The combination with an exhaust pipe having a pair of spaced ends, of a muffler cutout comprising a two-part casing having one part fixed relatively to one of said ends and the other part rotatable relatively to 100 the other end and to said fixed part thereby to open or close communication between said ends, said casing having one or more enlarged chambers, and tensioned means for maintaining said parts in juxtaposition. 105

13. The combination with an exhaust pipe having a pair of spaced ends, of a muffler cutout comprising a two-part casing having one part fixed relatively to one of said ends and the other part rotatable relatively to the 110 other end and to said fixed part thereby to open or close communication between said ends, said casing having one or more enlarged chambers, and means for returning the rotary part to its closed position. 115

14. The combination with an exhaust pipe having a pair of spaced ends, of a muffler cutout comprising a two-part casing having one part fixed relatively to one of said ends and the other part rotatable relatively to 120 the other end and to said fixed part thereby to open or close communication between said ends, said casing having one or more enlarged chambers, and means for wedging said parts in relatively tight engagement. 125

15. The combination with an exhaust pipe having a pair of spaced ends, of a muffler cutout comprising a two-part casing having one part fixed relatively to one of said ends and the other part rotatable relatively to 130

the other end and to said fixed part thereby to open or close communication between said ends, said casing having one or more enlarged chambers, tensioned means for maintaining said parts in juxtaposition, tensioned means for returning the rotary part to its normal position, and cam surfaces for wedging said parts in their closed position.

16. The combination with an exhaust pipe having a pair of spaced ends, of a muffler cutout comprising a two-part casing having one part fixed relatively to one of said ends and the other part rotatable relatively to the other end and to said fixed part thereby to open or close communication between said ends, said casing having one or more enlarged chambers, tensioned means for maintaining said parts in juxtaposition, tensioned means for returning the rotary part to its normal position, cam surfaces for wedging said parts in their closed position, and means connected with the rotary part for rotating it relatively to the fixed part and on its pipe section.

17. A cutout for a muffler comprising a two-part casing, one part adapted to be fixedly attached to a pipe section and the other part rotatable on a pipe section thereby to open or close communication between the pipe sections.

18. A cutout for a muffler comprising a two-part casing, one part adapted to be fixedly attached to a pipe section and the other part rotatable on a pipe section thereby to open or close communication between the pipe sections, said muffler cutout comprising a chamber of greater diameter than that of the pipe sections adjacent thereto.

19. A cutout for a muffler comprising a two-part casing, one part adapted to be fixedly attached to a pipe section and the other part rotatable on a pipe section thereby to open or close communication between the pipe sections, said muffler cutout comprising a chamber provided with a pair of sleeved ends, having greater diameter than that of said sleeved ends.

20. A cutout for a muffler comprising a two-part casing, one part adapted to be fixedly attached to a pipe section and the other part rotatable on a pipe section thereby to open or close communication between the pipe sections, said muffler cutout comprising a chamber having greater diameter than that of said pipe sections adjacent thereto and provided with a pair of inwardly extending walls and means carried thereby for returning the rotary section relatively to the other section.

21. A cutout for a muffler comprising a two-part casing, one part adapted to be fixedly attached to a pipe section and the other part rotatable on a pipe section thereby to open or close communication between the pipe sections, said muffler cutout comprising

a chamber having greater diameter than that of said pipe sections adjacent thereto and provided with a pair of inwardly extending walls, means carried thereby for returning the rotary section relatively to the other section, and wedging means carried exteriorly of the chamber for wedging one part in juxtaposition to the other.

22. The combination with a pair of spaced pipe sections, of a muffler cutout comprising an enlarged chamber consisting of a fixed part having a sleeve for attachment to one of said pipe sections and a rotary part having a sleeved end, a sleeve rigidly attached to the other pipe section for the reception of such sleeved end, said chamber parts having projecting walls, a spring carried thereby for returning the rotary part to its normal closed position, means carried by the chamber for wedging said parts in their closed position, and means carried by the fixed part and by said sleeve for maintaining said parts in tensioned relation relatively to each other.

23. A muffler cutout comprising a casing having a plurality of enlarged chambers, said casing comprising a fixed part and a rotary part, the latter rotatable simultaneously to open all the said chambers into communication with the muffler, or simultaneously to close such communications.

24. A muffler cutout comprising a casing having a plurality of enlarged chambers, said casing comprising a fixed part and a rotary part, and means for returning the rotary part to its normal position, the latter rotatable simultaneously to open all the said chambers into communication with the muffler, or simultaneously to close such communications.

25. A muffler cutout comprising a casing having a plurality of enlarged chambers, said casing comprising a fixed part and a rotary part, means for returning the rotary part to its normal position, and means for wedging the parts in closed position.

26. A muffler cutout comprising a casing having a plurality of enlarged chambers, said casing comprising a fixed part and a rotary part, means for returning the rotary part to its normal position, means for wedging the parts in closed position, and means for maintaining said parts in tensioned relation relatively to each other.

27. A muffler cutout comprising a casing having a plurality of enlarged chambers, said casing comprising a fixed part and a rotary part, means for returning the rotary part to its normal position, means for wedging the parts in closed position, and means for maintaining said parts in tensioned relation relatively to each other, one of said parts constructed to be fixedly attached to one pipe section and the other to rotate on another pipe section.

28. The combination with an exhaust pipe having a pair of spaced ends, of a muffler cutout comprising a part rotatable on one of said ends relatively to the other end thereby to open or close communication between said ends, the axis of the rotatable part being the same as the axis of the pipe.

29. The combination with an exhaust pipe having a pair of spaced ends, of a muffler cutout comprising a part rotatable on one of said ends relatively to the other end thereby to open or close communication between said ends, the axis of the rotatable part being the same as the axis of the pipe, said cutout having a projecting wall between the spaced ends.

30. The combination with an exhaust pipe having a pair of spaced ends, of a muffler cutout comprising a two-part casing having one part fixed relatively to one of said ends

and the other part rotatable relatively to the other end and to said fixed part thereby to open or close communication between said ends, said casing having a projecting wall between the spaced ends.

25

31. The combination with an exhaust pipe having a pair of spaced ends, of a muffler cutout comprising a two-part casing having one part fixed relatively to one of said ends and the other part rotatable relatively to the other end and to said fixed part thereby to open or close communication between said ends, said casing having one or more enlarged chambers and also having a wall between the spaced ends of the pipe.
